UNITED STATES PATENT OFFICE.

MAURICE B. FREDERICKS, OF WALTHAM, MASSACHUSETTS, ASSIGNOR, BY MESNE ASSIGNMENTS, TO JOSEPH L. LEVY, OF NEW YORK, N. Y.

PICKER FOR LOOMS.

1,416,274.

Specification of Letters Patent. Patented May 16, 1922.

Application filed April 13, 1921, Serial No. 461,039. Renewed April 11, 1922. Serial No. 551,471.

To all whom it may concern:

Be it known that I, MAURICE B. FREDERICKS, a citizen of the United States, and a resident of the city of Waltham, county of 5 Middlesex, and State of Massachusetts, have invented a certain new and useful Improvement in Pickers for Looms, of which the following is a specification.

This invention relates to a picker of the 10 character used on looms, and has for its object to provide an article of this character which will be strong and simple in construction and which will be extremely durable under constant use.

15 A further object of this invention is to provide a picker having those portions which contact with the loom shuttle renewable and arranged so that when the same become worn from contact with the pointed end of the 20 shuttle, they may be removed and new contacting portions inserted.

A further object of this invention is to provide those portions of a picker which contact with the shuttle of an extremely 25 tough and durable fibrous material so that the same can withstand the impact of the shuttle whereby an extremely durable article is produced.

With these objects and other objects which 30 may hereinafter appear in view, I have devised the particular arrangement of parts hereinafter set forth and more particularly pointed out in the claims appended hereto.

Reference is to be had to the accompanying drawing, forming a part hereof in which—

Figure 1 is a perspective view showing the picker in place together with surrounding portions of a loom and the shuttle which 40 is struck by the picker.

Figure 2 is a face view of the picker, portions of the same being broken away to disclose the construction,

Figure 3 is a sectional view on the line 45 3—3 of Figure 2 looking in the direction of the arrows,

Figure 4 is a perspective view of the end of the picker showing my improved protective means therefor.

50 Figure 5 shows a modified form of protective means for the picker head.

Throughout the various views of the drawing, similar reference characters designate similar parts.

55 In the preferred embodiment of my inven-

tion, 1 indicates the body portion of the picker which is in the form of a flat section of fibrous material such as horn, raw-hide or fiber. I have found that fiber or a similar fibrous material is particularly adaptable for 60 use in forming pickers of this character.

Near one of its ends, the picker is provided with an aperture 14 through which a bar 2 extends. This bar 2 is a conventional portion of a loom and acts as a guide member 65 for the picker which slides thereon and strikes against the shuttle 3 sending the same across the loom.

At one of its ends, the picker is provided with a pair of reinforcing strips 5 which 70 form a thickened end at the wider end of the body portion 1 of the picker. These strips 5 co-operate with a narrow strip 15 secured between them to form enclosing means for the wider end of the body portion and form 75 a thickened portion at that point. Portions of the strips 5 and 15 are positioned so that they unite in forming an aperture 14. The outer end of the body portion 1 is narrowed as at 16 and on either side of the same is 80 secured a pair of reinforcing blocks 7 and 8, said blocks 7 and 8 being secured to the body portion 1 by means of rivets or the like, and forming a thickened portion at the narrowed end of the picker. Thus the 85 picker is provided with a pair of thickened ends and a central thinner portion. A strip 16 at the narrower end of the body portion is inserted between the ends of the blocks 7 and 8 and is in all respects similar to that 90 designated at 15.

At 10 are a pair of inserts or plugs of a tough fibrous material similar to that of which the body of the picker is formed. These plugs 10 are arranged so that the grain 95 of the material from which they are constructed extends transversely of the shuttle and similarly transversely of the picker, thereby providing strengthened portions of the picker at the point of contact of the 100 shuttle therewith. The plugs 10 are readily removable when worn, and new plugs may be replaced. It will be seen that these plugs 10 are so placed that when the picker is moved on its support 2 by means of a bar 11 105 extending through an aperture 12 in the body of the picker, the pointed end 13 of the shuttle will contact with the plug 10. When one of the plugs 10 becomes worn by constant contact with the shuttle the picker is 110

merely reversed on its support 2 to bring the plug on the opposite side of the picker so that the same faces the shuttle and contacts therewith.

5 The fact that the grain of the plugs runs transversely of the shuttle enables the plugs to be capable of withstanding the impact of the pointed end of the shuttle to a greater extent than would be the fact if the grain 10 extended parallel to the shuttle, and in view of the fact that these plugs are renewable, very little wear to the body of the picker occurs.

In order that the portions of the picker 15 adjacent the plugs 10 in the head thereof will be reinforced against the blows of the shuttle and that the strips 7 and 8 will be prevented from separation I provide a reinforcing means as at 17. This reinforcing 20 means is in the nature of a binding strip arranged to fit over each end of the head of the picker as disclosed in Figure 4. As disclosed the portion 18 of the reinforcing strips may be countersunk into the part 1 of 25 the picker.

Figure 5 shows a modified protective means in the nature of a sleeve 19 which fits over the end of the picker and which is provided in two of its opposite walls with 30 openings 20 through which the shuttle can contact with the plug 10.

From the foregoing it is obvious that my invention is not to be restricted to the exact embodiment shown but is broad enough to cover all structures coming within the scope 35 of the annexed claims.

What I claim is:

1. A device of the class described comprising a picker having a central section of a single thickness of material, said section 40 having a narrowed and a wide end, each of said ends being reinforced by the addition of pieces of material secured on opposite faces of the central section, removable contact-plugs located in the reinforced narrow 45 end, said picker having oppositely disposed openings extending through its widest reinforced end.

2. A device of the class described comprising a picker having a central body portion 50 of a single thickness, reinforcing strips secured at the ends of said body portion and forming thickened portions, a guide receiving aperture extending through one of said thickened portions, a pair of plugs of fibrous 55 material inserted in the other thickened portion and a reinforcing binder embracing the thickened portion in which the plugs are inserted.

Signed at the city, county and State of 60
New York this 4th day of April, 1921.

MAURICE B. FREDERICKS.
